Joseph Leeds

UNITED STATES PATENT OFFICE.

JOSEPH LEEDS, OF PHILADELPHIA, PENNSYLVANIA.

IMPROVEMENT IN VENTILATORS FOR BUILDINGS.

Specification forming part of Letters Patent No. 39,937, dated September 15, 1863; antedated December 14, 1862.

To all whom it may concern:

Be it known that I, JOSEPH LEEDS, of the city of Philadelphia, in the State of Pennsylvania, have invented a new and useful Improvement in Ventilators for Buildings; and I do hereby declare that the following is a full, clear, and exact description of the construction and operation of the same, reference being had to the accompanying drawings, making a part of this specification, in which—

Figure 1 is a front view, and Fig. 2 a vertical central section, of the said improved ventilator, like letters indicating the same parts when in both figures.

Ventilators of this class generally open into a flue, and require to be placed near the ceilings of the room to be ventilated; and, in consequence of the elevated position, at least two separate cords have heretofore been required to be suspended from each, in order to afford appropriate means of operating the vibratory valve-plate as occasion required.

The object of my invention is to render one cord sufficient for the purpose, and thus to simplify the construction and mode of operation, and lessen the cost, without diminishing the requisite power of controlling the ventilator properly.

It consists, substantially as hereinafter described, in so constructing and attaching the vibratory valve-plate to its frame or case that the gravitation of the former will give it a constant tendency to fall inward toward the flue, while the single cord suspended therefrom, and extending down to within convenient reach from the floor of the room, has attached within its usual ornamental tassel a weight, which can be regulated to slightly overcome the said gravitating tendency of the valve-plate, so that when it shall be desired either to open or close the ventilator all that will be necessary will be that the operator shall either lift upward or pull downward, accordingly, the said tassel to effect the object.

In the drawings, A is the frame or case of the ventilator; B, the vibratory valve-plate; C, the operating-cord; D, the ornamental tassel, and E the adjustable weight. The case A may be made to present in front any of the ordinary forms, having an ornamenteally-perforated or skeleton face, with a sufficiently long vertical opening, a' , for the required free vertical motions of the cord

which passes through it, and also a grooved pulley, a^2 , within its upper part, for guiding the said cord. The upper end and sides of the valve-plate B fit against the back edges of the case A, while its lower end fits between the lower ends of the sides of the same and turns upon a journal, b' , which projects from each side of the plate and enters the sides of the case, the said lower end of the plate B being curved sufficiently for the purpose, and the edges of the sides of the case A being sloped inward toward their lower ends, so as to allow the valve-plate B to have, when in contact with the said edges, an inclined position toward the flue, which latter is indicated by the dotted lines $x\ x$, and consequently a constant tendency to fall backward or into the flue, substantially as is indicated by the dotted lines $y\ y$ in Fig. 2. The cord C has its upper end fixed to the upper part of the valve-plate B, and extends down over the pulley a^2 , and through the vertical opening a' , so as to bring its tassel D within convenient reach from the floor of the room, as seen in the drawings. Within the tassel D the hollow case E is fixed to the end of the cord, so as to be concealed therein, and into this case E shot or other weights are placed in sufficient quantity to slightly overcome the falling tendency of the valve-plate B when the same is in the inclined position seen in Fig. 2.

In the operation of this invention it will be readily seen that when the weight E is pulled downward by hand until the valve-plate B is closed against the case A the former will so remain until the said weight is lifted by the operator, when the valve-plate will fall backward, and thus open the ventilator for the passage of air into the flue.

Having thus fully described my improvement in ventilators and pointed out its utility, what I claim as new therein, of my invention, and desire to secure by Letters Patent, is—

Operating the valve-plate B of the ventilator by means of its gravitating tendency, in combination with the one cord, C, and a weight, E, attached to the lower end of the said cord, substantially in the manner described.

JOSEPH LEEDS.
